CONCEALED POCKET

Herman B. Welch, West Bend, Wis., assignor to
 Amity Leather Products Co., West Bend, Wis.,
 a corporation of Wisconsin

Application March 18, 1935, Serial No. 11,605

1 Claim. (Cl. 150—36)

This invention appertains to pocket-books, and more particularly to ladies' hand-bags, and has for one of its salient objects the provision of novel means for forming a pocket in the bag, and novel means for forming a closure therefor.

Another primary object of the invention is to provide a pocket located in the bag in such a manner, and covered by a sealing flap in such a way, that the pocket will be normally hid 10 from the casual observer, thereby rendering the pocket of a secret nature.

A further object of the invention is the provision of a lady's hand-bag having a concealed pocket arranged either in the body of the bag 15 or the main flap of the bag, and provided with a "Zipper" fastener, with an auxiliary flap overlying the entrance to the pocket for serving the triple function of, first, concealing the pocket entrance; second, covering the unsightly appearance of the fastener when the bag is open; and, third, serving as a guard to prevent injury 20 and wear to the inside of the bag by the fastener.

A further important object of the invention is to arrange the entrance of the pocket in such 25 a manner that the closure fastener therefor will lie parallel with and flat against the main flap or the body of the bag, as the case may be, whereby a relatively thin, non-bulky closure will be had.

30 A still further object of the invention is to provide novel means for arranging the pocket and the closure therefor, so that the pocket can extend in either direction from the closure, or in both directions from the closure.

35 With these and other objects in view, the invention consists in the novel construction, arrangement, and formation of parts, as will be hereinafter more specifically described, claimed, and illustrated in the accompanying drawings, 40 in which drawings:

Figure 1 is an elevation of the main flap of a hand-bag, showing the inside thereof with parts thereof broken away and in section to illustrate structural details, the body of the bag being entirely broken away.

45 Figure 2 is a transverse section through the main flap of the bag, taken substantially on the line 2—2 of Figure 1, illustrating the novel construction of the pocket, the concealing flap, and the closure therefor.

50 Figure 3 is a front elevation of a lady's hand-bag, with the main flap in its open position, parts of the hand-bag being shown broken away and in section to illustrate structural details, the 55 view illustrating a modified form of the inven-

tion with the pocket running in opposite directions from the closure thereof.

Figure 4 is a fragmentary transverse section through the hand-bag, taken substantially on the line 4—4 of Figure 3, the view being on a 5 slightly enlarged scale.

Figure 5 is an elevation of a flap of a lady's hand-bag, showing the inside face thereof, parts of the view being shown broken away and in section, the view illustrating another form of 10 the invention with the closure of the pocket arranged adjacent to the outer edge of the main flap.

Figure 6 is a front elevation of a lady's handbag, with the main flap open and partially broken 15 away, parts of the hand-bag being also shown broken away and in section to illustrate structural details, the view illustrating a further form of 20 the invention with the pocket extending into the body of the bag from the closure;

Figure 7 is a front elevation of a lady's handbag, with the flap broken away, and with parts of the body of the bag broken away and in section 25 to illustrate structural details, the view showing a still further form of the invention with the pocket formed in the front face of the body of the bag.

Referring to the drawings in detail, wherein similar reference characters designate corresponding parts throughout the several views, the 30 letter F generally indicates the main closure flap of a lady's hand-bag. The outer wall or back 10 of the flap F forms a continuation of the outer face of the body of the bag in the usual manner, and the invention relates to the novel means of 35 forming a pocket 11 on the inner face of the flap. The inner face of the main flap F is covered by an inner wall or piece 12, preferably formed from leather or other wear-resisting material, and this piece or wall 12 is sewed at its 40 transverse edges, and its outer longitudinal edge, as at 13, to the transverse and outer longitudinal edge of the back or outer wall 10 of the flap.

It is to be noted that the transverse stitches 45 terminate short of the inner longitudinal edge of the wall 12, and this provides an auxiliary bendable flap 14. Sewed between the back 10 and the inner wall 12 is a partition 15 formed of fabric, or the like. This partition forms a pocket between the same and the wall 12 and a space 50 between the same and the back 10. In the space between the back 10 and the partition 15 is arranged the novel pocket 11. A finishing strip 16 of leather or the like is sewed across the partition 15, and the back of the body of the bag, and 55

this finishing strip 16 is provided with a longitudinally extending, relatively wide slot or cut-out portion 17, which forms an entrance to the space between the back 10 and the partition 15. 5 The pocket 11 is preferably formed by a silk lining or other material 18, and this lining is folded back upon itself on a longitudinal line, and has its longitudinal edges sewed respectively, as at 19 and 20, to the finishing strip 16 on one side 10 of the slot 17, and to the finishing strip and the partition 15 on the other side of the slot 17. The side transverse edges of the lining are then suitably sewed together, as at 21. A "Zipper" fastener 22 is utilized to close the slot and the entrance to 15 the pocket 11, and the tapes of the fastener are sewed respectively to the finishing strip 16 on opposite sides of the slot 17 by the line of stitches 19 and 20 heretofore referred to.

It is to be noted that the "Zipper" fastener lies 20 flat against and parallel with the back of the flap, and hence a thin, non-bulky closure is formed for the pocket.

In accordance with this invention, the auxiliary flap 14 completely overlies the "Zipper" fastener 22, and the entrance to the pocket 11, and hence the entrance and the pocket is normally hid from the view of a casual observer. Particular stress is laid on the bendable flap 14, in that the flap 30 protects the body of the pocket-book from wear by the abrasive action of the metal of the fastener, and hides the unsightly appearance of the fastener from view.

Various modifications of the invention can be made, and in Figures 1 and 2 the pocket 11 is shown extending into the flap, and this pocket can be so formed as to extend into the body of the pocket-book, instead of the flap, or both into the flap and in the body of the pocket-book.

In Figures 3 and 4 the pocket is shown extending both into the flap and body portion of the pocket-book or hand-bag. In Figures 3 and 4 the pocket-book or hand-bag is generally indicated by the reference character B, and the same includes the body 25 and main closure flap 26. 40 The closure flap 26 forms a continuation of the back of the body, and this flap has sewed thereto an inner wall or piece 27, which corresponds to the wall 12 in Figures 1 and 2. A partition wall 28 extends the full length and width of the back 50 of the pocket-book, and is sewed at its transverse and longitudinal edges to the back. This partition piece has a facing of leather or other wear-resisting material 29 on its inner face between the body of the pocket-book 25 and the flap 26. This 55 finishing piece 29 preferably extends a short distance into the body of the pocket-book and into the flap and under the inner wall 27 of the flap. The finishing piece 29 and the partition wall 28 are provided with a longitudinally extending, 60 relatively wide slot or cut-out portion 30, which forms the entrance to the novel pocket. The pocket is preferably formed by a piece of lining 31, or other material, which extends substantially the full length and width of the back, and the ends of the lining are folded back upon themselves with the edges thereof sewed to the partition wall 28 on opposite sides of the slot 30. The 65 sides of the material 31 are suitably sewed together, as at 32. A "Zipper" fastener is provided for closing the entrance to the pocket, and the tapes of the fastener are sewed to the partition wall 28 and the ends of the lining material 31 on opposite sides of the slot 30. This forms the 70 pocket extending in opposite directions from the closure fastener, and it is to be noted that the 75

auxiliary flap 33 of the inner wall 27 completely overlies the closure fastener.

In Figure 5 is illustrated another form of the invention, in which the pocket is formed solely in the main flap of the hang-bag, and extends from the outer longitudinal edge of the flap into the body portion of the flap. The flap shown in Figure 5 is generally indicated by the reference character 35, and in this form the inner wall or piece 36, which corresponds to the inner wall 14 10 of that form of the invention shown in Figures 1 and 2, is sewed, as at 37, at its transverse edges only to the back wall of the flap.

This inner wall 36 extends into the body of the pocket-book for a short distance, and may constitute the finishing strip for the inner face of the back of the body of the bag. This leaves the outer longitudinal edge of the inner wall 36 free to form an auxiliary closure flap 38. Sewed between the inner wall 36 and the back of the flap 39 is a partition wall 40, and this wall terminates short of the outer free longitudinal edge of the inner wall 36. A finishing piece 41 of leather or the like is sewed to the inner face of the back 39 over the outer edge of the partition wall 40 and under 20 the auxiliary flap 38. This finishing piece 41 is provided with the relatively wide, longitudinally extending slot or cut-out portion 42. The lining 43 for the pocket is folded upon itself, and has its longitudinal edges sewed to the finishing piece 20 on opposite sides of the slot 42, and the ends of the lining are sewed together as at 44. A "Zipper" 30 fastener 45 is provided for closing the slot, and its tapes are sewed to the opposite walls of the slot 42. By this arrangement the entrance to the 35 pocket is disposed adjacent to the outer edge of the main flap, and the auxiliary flap 38 is so disposed as to still cover the entrance.

In Figure 6 a still further form of the invention is shown, and in this form the pocket extends inwardly from the closure flap into the body of the bag. In Figure 6 the hand-bag is generally indicated by the reference character 50, and the same includes the body 51 and the main closure flap 52 therefor. This flap 52 forms a 40 continuation of the back of the bag, and the flap has sewed thereto an inner wall 53, the inner longitudinal edge of which is left free to provide the auxiliary flap 54. A finishing piece or partition wall 55 is sewed at its longitudinal and transverse edges to the back of the bag, and the same is provided with a longitudinally extending, relatively wide slot 56 under the auxiliary flap 54. A lining 57 is disposed in the body of the bag between the back of the bag and the partition wall 55, and this lining is folded back upon itself and has its longitudinal edges sewed respectively to the wall 55 on opposite sides of the slot 56. The end edges of the lining are sewed together, as at 58. A "Zipper" fastener 59 is provided for closing 60 the entrance to the pocket, and the tapes of the fastener are sewed to the wall 55 on opposite sides of the slot 56, and to the longitudinal edges of the lining 57.

In Figure 7 I have shown the pocket formed in 65 the body of the bag adjacent to the front wall thereof. The hand-bag in Figure 7 is indicated by the reference character 60, and the same includes the main body portion 61 with a main closure flap 62 therefor. This closure flap forms 70 a continuation of the back of the pocket-book in the usual way. In between the front wall 63 of the pocket-book, which also forms a continuation of the back and the main body portion of the bag, I arrange a partition 64, which, in ac- 75

cordance with this invention, is formed from a plurality of plies of material. The outer ply is provided with a longitudinally extending slot 65, and a lining 66 is arranged between the plies to 5 form the novel pocket. The lining is folded back upon itself on a longitudinal line, and its longitudinal edges are sewed to the outer ply on opposite sides of the slot 65. The ends of the lining 66 are sewed together as at 67. By this construction I form the pocket directly in a partition wall, and the entrance to the pocket can be closed by a "Zipper" fastener 68. The tapes of the "Zipper" fastener are sewed to the outer ply of the partition wall, and to the longitudinal edges of the 15 lining material 66 on opposite sides of the slot 65. Attention is invited to the fact that the front wall 63 of the body of the pocket-book has its upper edge left free so as to provide an auxiliary flap 69, and this auxiliary flap 69 overlies the slot 20 65 and the "Zipper" fastener 68. Thus, the pocket and the closure therefor are normally concealed from view.

By referring to the various forms of the invention, it will be noted that in all forms the fastener 25 lies flat against and parallel with the wall with which the same is associated, as hereinbefore explained, and hence provides a thin, flat closure.

From the foregoing description, it can be seen that a novel concealed pocket is provided, in

which all loss of matter placed therein is prevented, and in which the entrance is completely hidden, even when the bag is in its open position.

Concealed pockets are known in the art, but I am the first to provide a complete closure for the 5 secret pocket, and to provide means for completely covering the fastener and the closure so that the same is hidden from an observer.

Changes in details may be made without departing from the spirit or scope of the invention, 10 but what is claimed as new is:

In a lady's hand-bag, a body, a main closure flap for the body including a back, an inner wall for said flap stitched at its side transverse edges and one longitudinal edge to the back, a partition wall disposed between the back and the inner wall and stitched thereto, a finishing strip secured to the back and the inner edge of the partition wall, said finishing strip having a longitudinally extending slot therein, a piece of material folded 15 back upon itself disposed between the partition wall and the back having its longitudinal edges secured to the finishing strip on opposite sides of the slot, means securing the side edges of the material together, and a slide fastener for the walls 20 of said slot, the inner wall of the flap having an auxiliary bendable flap thereon overlying said fastener. 25

HERMAN B. WELCH.
